UNITED STATES PATENT OFFICE.

FIDEL FEEDERLE, OF OBERNDORF-ON-THE-NECKAR, GERMANY, ASSIGNOR TO WAFFENFABRIK MAUSER, AKTIENGESELLSCHAFT, OF OBERNDORF-ON-THE-NECKAR, GERMANY.

AUTOMATIC PISTOL.

1,427,097.

Specification of Letters Patent. Patented Aug. 29, 1922.

Application filed June 17, 1921. Serial No. 478,349.

To all whom it may concern:

Be it known that I, FIDEL FEEDERLE, engineer, citizen of the German Republic, residing at Oberndorf-on-the-Neckar, Germany, have invented certain new and useful Improvements in Automatic Pistols (for which application was filed in Germany on October 4, 1917, Serial No. W. 49,847, in the name of Waffenfabrik Mauser, Aktiengesellschaft, of Oberndorf-on-the-Neckar, Germany, with my knowledge and consent), of which the following is a specification.

This invention relates to automatic pistols with movable barrel and an interlocking member or block arranged to move in the lock frame and to interlock the barrel and the breech obturating member or bolt. The object of the invention is to effect improvements in this type of pistol which are more particularly hereinafter described.

The invention is shown in the drawing in which—

Fig. 1 illustrates the improved automatic pistol partly in longitudinal section with the hammer in its cocked position,

Fig. 2 is a rear end view,

Fig. 3 a cross section on the line A—B of Fig. 1,

Fig. 4 a perspective view of the interlocking block,

Fig. 5 a perspective view of the lock fastener and the trigger,

Fig. 6 is a more detailed view of parts of Fig. 1 showing the action of the trigger and its spring on the magazine fastener.

Figs. 7 and 8 are longitudinal sections of the firearm as seen from the side opposite to that shown in Fig. 1, Fig. 7 illustrating the pistol in its normal position with the hammer cocked, whilst Fig. 8 shows the position of its parts after the recoil of the barrel and the bolt due to the firing of the pistol.

Fig. 9 is a perspective view of a detail and Figs. 10 and 11 are perspective views of the rear part of the bolt chamber and the lock-housing respectively.

In the drawings 1 is the barrel and 2 a rearward prolongation of the barrel shaped in the form of a bolt chamber. 3 is the obturating member or bolt arranged to slide

in the bolt chamber, 4 the lock frame, 5 the lock housing, 6 the interlocking block, and 7 the lock fastener. The latter takes the form of a slide member that is adapted to slide in a vertical direction on a part of the lock housing situated at the front of the trigger. Pivotally mounted intermediate its ends, as at 8', in a longitudinal recess formed in the top face of the illustrated slide member 7 (Fig. 5) is a lever 8 whose forward arm is acted upon by helical spring 9 (Fig. 1) which fits in a vertical socket in said slide that opens into the above-mentioned recess, said spring keeping the front end of the lever 8 constantly raised and the rear end constantly pressed downward against the trigger 10. Hence the lever 8 and its spring 9 form tensioning members for the trigger, which latter is pivoted in the lock frame by means of its pintles 10'; and it will also be apparent that the slide 7 may be regarded as suspended by the rear arm of the lever 8 on the top face of the trigger, while being guided in front in the trigger bow in the vertical direction. The size of the forward arm of the lever 8 is such that, when the trigger is pulled, i. e. when the said forward arm is moved downward, it engages with the notched upper end of the magazine fastener 11, as shown in Fig. 6, and prevents the magazine from being unintentionally released, as by vibrations arising during discharges.

Due to the pivotal suspension of the slide, by means of the lever 8 as above explained, on the top face of the trigger, and to the upward pressure exerted by the spring 9 against the front arm of the lever, the said spring and lever will conjointly act to hold the slide in its top position in which it engages with the downwardly extending projection 12 of the lock frame 4 and thus locks said frame in place. The lower end of the lock frame fastener 7 is serrated at its side 95 that faces the trigger so as to enable it to be conveniently pulled downward with a finger for the purpose of disengaging it from shoulder 12 so as to permit the removal of the lock-frame 4 when taking the firearm to pieces in the known manner.

The usual rod-lever or sear 13, Fig. 7, is

pivottally mounted in the detachable lock-frame 4 which is held firmly in position in the firearm. At its rear end the sear 13 has a lateral projection 14 (Fig. 9) which is 5 adapted to engage with a catch 15 of the hammer 16. The sear, which has another lateral projection 17 at its front end (Fig. 9) that rests upon the trigger 10 (Fig. 7), is affected by a spring 18 in such a way that it 10 automatically engages with the catch 15 of the hammer when the latter is cocked. Also pivottally mounted in the lock-frame 4 above the sear 13 is a second lever or sear 19 which is also pressed by the spring 18 of the 15 sear 13 into a position in which, when the hammer 16 is moved back into its tensioned or cocked position, a rear lateral projection 20 of the sear 19 engages with the front stopping surface 21 of the hammer (Fig. 9). 20 The sear 19 has a projection 22 at its front end, and the dog 23 on the interlocking block 6 cooperates with this projection 22 when the obturating bolt 3 reaches the obturating position.

25 In accordance with the invention the interlocking block 6 is made of a solid piece and has a front projection 24 that enters into a slot 25 in the lock-frame 4 (Fig. 1). Two abutting surfaces 26 (Fig. 4) at the sides of 30 the projection 24 are pressed by the striking spring 27 with the aid of a pivoted hook 28 against surfaces of the lock-frame 4 situated at both sides of the said slot 25. When the interlocking block 6 is in this position it is 35 held firmly in the lock-frame 4 and cannot fall out when the pistol is taken to pieces.

When the parts of the pistol are in their normal positions two top projections 29 on block 6 (Fig. 1) engage with notches 36 in 40 the lower surface of the obturating bolt 3 so that the block is coupled with the bolt.

The bolt chamber 2 which consists in a known manner of a prolongation of the barrel 1 has a downwardly extending projection 30 that abuts against a front surface of the interlocking block 6 so that on the recoil of the barrel due to a discharge the interlocking block is moved backward against the action of the striking spring 27 and its rear 45 downwardly projecting cam 31 (Fig. 1) is pressed down into a cavity in the lock-frame 4. When this movement is completed the obturating bolt 3 is released and moves back alone whilst the barrel is arrested.

55 During its displacement upon the lock housing 5 the bolt chamber 2 is guided in slides arranged at the front and rear of the lock. In the illustrated type of pistol the front slide consists of a L shaped rail 32 60 integral with the barrel 1 or with the bolt-chamber 2. As shown in Fig. 3 the said rail slides in a groove of corresponding shape at the front end of the lock housing 5.

The rear guide member of the lock-chamber 65 consists of a tongue 33 (Figs. 1 and 2)

at the bottom of the bolt-chamber which, as shown in Fig. 10, is also L shaped. The lock housing 5 is provided at its rear end with two inwardly projecting guide ledges 34 (Figs. 2 and 11) shaped so as to fit into two lateral grooves at the sides of the said tongue and to guide the barrel or bolt chamber during its sliding movement. By guiding the bolt chamber 2 on the lock housing 5 in this manner the bulky lateral protuberances 70 hitherto employed for this purpose on the lock housing are dispensed with, so that a more advantageous shape of the weapon results.

The mode of operation of the afore-described parts is, in general known, so that a detailed description is unnecessary.

This mode of operation only differs with respect to the two bar levers or sears 13 and 19 whose operation, when the weapon is discharged, is as follows:

1. When firing single shots.

When a shot is fired the barrel 1, which is coupled with the bolt 3 by the engagement 90 of the projections 29 on the block 6 in the notches 36 in said bolt moves back with the block and bolt 3 until the cam 31 at the rear end of the block enters into the previously mentioned cavity in the lock frame 4. At 95 this moment the coupling between the obturating bolt and the barrel ceases, due to the disengagement of the projections 29 from notches 36, the motion of the barrel now being stopped by the detained locking block 6 100 against which the downwardly extending projection 30 of the barrel strikes. The bolt member 3 continues its backward movement alone and cocks the hammer 16 (Fig. 8). By the rear lug 14 on the sear or rod lever 13 105 engaging with the catch 15 of the hammer, this latter is then held in its cocked position. The obturating bolt 3 is now pushed forward in a known manner by its thrust spring 35 (Figs. 7 and 8) that was tensioned 110 during the backward motion of the bolt. The forward motion of the bolt continues until its notches 36 are opposite the projections 29 of the interlocking block 6 when these projections will automatically fly into 115 the said notches, due to the known spring action of the block, and the obturating bolt and the barrel will be recoupled to each other so that the bolt and the barrel move forward together until the downwardly extending projection 30 of the barrel strikes 120 against the top 37 on the lock-frame 4 (Fig. 7). If the trigger 10 is now pulled the rear end of the sear or rod lever 13 is depressed and its projection 14 thereby moved away 125 from the catch 15 of the hammer 16 which now swings upwards and fires a new cartridge which, during the forward movement of the obturating bolt, slipped in a known manner from the magazine into the breech 130

of the barrel. These operations recur each time the trigger 10 is pulled.

2. Firing uninterrupted series of shots.

- 5 To do this it is only necessary to keep the trigger pulled back into the position shown in Fig. 8 so as to prevent all engagement between the sear 13 and the catch of the hammer. In such cases the hammer 16, each 10 time it is cocked by the recoil of the obturating bolt 3, will be held for a while in its cocked position by means of the rear lateral projection 20 of the auxiliary sear or lever 19 which is forced down in front of the retaining surface 21 of the hammer. But at 15 the moment the obturating bolt 3, which moves forward again after the discharge, is recoupled with the barrel and again occupies its obturating and interlocking position, i. e., 20 at the moment the striking projection 23 of the interlocking block 6 knocks against the projection 22 of the lever 19 and raises the rear end 20 of the latter above the retaining surface 21 of the hammer against the action 25 of the spring 18, the hammer will be released and fly forward to fire off a new cartridge. These operations recur automatically and without interruption as long as the trigger 10 is kept pulled as shown in 30 Fig. 8.

I claim:

1. In an automatic pistol, a movable barrel, an obturating member adapted to slide in a prolongation of the said barrel, a lock-housing, a removable lock-frame in the said lock-housing, a movable interlocking block in the said frame adapted to couple the barrel and the obturating member to each other, a trigger guard, a downwardly extending projection on the said lock-frame, and a vertically movable member at the front of the trigger normally engaged with the said downwardly extending projection to secure the lock-frame in the lock-housing. 35
2. In an automatic pistol, a movable barrel, an obturating member adapted to slide in a prolongation of the said barrel, a lock-housing, a removable lock-frame in the said lock-housing, a movable interlocking block in the said frame adapted to couple the barrel and the obturating member to each other, a trigger guard, a downwardly extending projection on the said lock-frame, a vertically movable member at the front of the trigger cooperating with the said downwardly extending projection and adapted to secure the lock-frame in the lock-housing. 40
3. In an automatic pistol, a movable barrel, an obturating member adapted to slide in a prolongation of the said barrel, a lock-housing, a removable lock-frame in the said lock-housing, a movable interlocking block in the said frame adapted to couple the barrel and the obturating member to each other, a trigger guard, a downwardly extending projection on the said lock-frame, a vertically movable member at the front of the trigger cooperating with the said downwardly extending projection and adapted to secure the lock-frame in the lock-housing, 45 a trigger, a spring and a pivotally mounted lever in the vertically movable member, the spring being adapted to keep the rear end of the said lever pressed against the trigger, a cartridge magazine, and a magazine fastener, the front end of the said lever being adapted to lock the said fastener when the trigger is pulled. 50
3. In an automatic pistol, a movable barrel, an obturating member adapted to slide in a prolongation of the said barrel and to recoil when the pistol is fired, a lock-housing, a removable lock-frame in the said lock-housing, a movable interlocking block in the said frame adapted to couple the barrel and the obturating member to each other, a trigger guard, a downwardly extending projection on the said lock-frame, 70 a vertically movable member at the front of the trigger cooperating with the said downwardly extending projection and adapted to secure the lock-frame in the lock-housing, a trigger, a hammer, means for cocking the said hammer, a primary sear for keeping the hammer in its cocked position and adapted to be disengaged from the hammer as long as the trigger is kept pulled, and a secondary sear adapted to hold the 75 hammer in its cocked position during the recoil of the said obturating member and to be moved out of engagement with the hammer by the said interlocking block when the obturating member returns from the recoil into its front position. 80
4. In an automatic pistol, a movable barrel, an obturating member adapted to slide in a prolongation of the said barrel, a lock-housing, a removable lock-frame in the said lock-housing, a hammer actuating spring, an interlocking block movable in the said frame adapted to couple the barrel and the obturating member to each other, supporting surfaces in the lock-frame and corresponding supporting surfaces on the said interlocking block, the block being pressed with its supporting surfaces against the supporting surfaces of the lock-frame and being thus held so as to be freely movable in the 90 lock-frame, a trigger guard, a downwardly extending projection on the said lock-frame, and a vertically movable member at the front of the trigger cooperating with the said downwardly extending projection and being 95 held so as to be freely movable in the lock-frame, a trigger guard, a downwardly extending projection on the said lock-frame, and a vertically movable member at the front of the trigger cooperating with the said downwardly extending projection and being 100 held so as to be freely movable in the lock-frame, a trigger guard, a downwardly extending projection on the said lock-frame, and a vertically movable member at the front of the trigger cooperating with the said downwardly extending projection and being 105 held so as to be freely movable in the lock-frame, a trigger guard, a downwardly extending projection on the said lock-frame, and a vertically movable member at the front of the trigger cooperating with the said downwardly extending projection and being 110 held so as to be freely movable in the lock-frame. 115
5. In an automatic pistol, a movable barrel, an obturating member adapted to slide in a prolongation of the said barrel, a lock-housing, a removable lock-frame in the said lock-housing, a movable interlocking block in the said frame adapted to couple the barrel and the obturating member to each other, a trigger guard, a downwardly extending projection on the said lock-frame, a vertically movable member at the front of the trigger cooperating with the said downwardly extending projection and adapted to secure the lock-frame in the 120 lock-housing, guide members on the barrel and its prolongation, each said guide member comprising a bar of L shaped cross section, and grooves in the lock-housing adapted to embrace the said bar. 125

6. In an automatic pistol, the combination of a movable barrel; a bolt slidable therein; a lock frame; an interlocking block movable in said frame and engageable directly with the bolt to couple the latter to the barrel to move together during the initial portion of the recoil movement of the barrel; a spring operative upon said block constantly tending to effect such engagement; means for automatically disengaging said block from said bolt when the said initial portion of its recoil movement has been completed; and a return spring for said bolt, the first-named spring automatically re-engaging said block and bolt during the last portion of the return movement of the bolt, whereby the barrel is returned to normal position.
7. In an automatic pistol, the combination of a movable barrel; a bolt slidable therein and formed with one or more notches; a lock frame provided with a cavity; an interlocking block movable in said frame and having one or more projections for engagement in said notches to couple the bolt and barrel together to move as a unit during the initial portion of the recoil movement of the bolt, said block having a lug which is movable into said cavity at the completion of the said initial portion of the recoil movement of the bolt to disengage said projections; a return spring for the bolt; and a spring operative upon said block to withdraw said lug from said cavity and re-engage said projections and notches during the last portion of the return movement of the bolt, whereby the barrel is returned to normal position.
8. In an automatic pistol, a movable barrel; a bolt slidable therein; a removable lock frame; a housing wherein said frame is mounted and comprising a trigger guard; a projection on said frame; a trigger; a hammer associated therewith; and a vertically movable member arranged in said housing in front of the trigger and engaged with said projection to secure the frame in the housing.
9. In an automatic pistol, a movable barrel; a bolt slidable therein; a removable lock frame; a housing wherein said frame is mounted and comprising a trigger guard; a projection on said frame; a trigger; a hammer associated therewith; a vertically movable member arranged in said housing in front of the trigger and normally engaged with said projection to secure the frame in the housing; a cartridge magazine; a magazine fastener; and means carried by said movable member for locking said fastener when the trigger is pulled.
10. In an automatic pistol, a movable barrel; a bolt slidable therein; a removable lock frame; a housing wherein said frame is mounted and comprising a trigger guard; a projection on said frame; a trigger; a hammer associated therewith; and a vertically movable member arranged in said housing in front of the trigger and normally engaged with said projection to secure the frame in the housing; a cartridge magazine; a magazine fastener; and means carried by said movable member for locking said fastener when the trigger is pulled.
11. In an automatic pistol, the combination of a lock housing comprising a trigger bow; a removable lock frame in said housing; a trigger pivotally mounted in the lock housing; a vertically movable member disposed in the trigger bow in front of the trigger and slidably engaged with a part of the housing to be guided thereby, said member being pivotally suspended upon the top face of the trigger; and a depending projection on the lock frame normally engaged by said member to secure the lock frame in the housing.
12. In an automatic pistol, the combination of a lock housing comprising a trigger bow; a removable lock frame in said housing provided with a depending projection which extends within the trigger bow; a trigger pivotally mounted in the lock housing; and a vertically movable member disposed in the trigger bow in front of the trigger and slidably engaged with a part of the housing to be guided thereby; said member being pivotally suspended upon the top face of the trigger and normally held in raised position with its upper end engaged with said projection to secure the lock frame in the housing.
13. In an automatic pistol, the combination of a lock housing comprising a trigger bow; a removable lock frame in said housing; a trigger pivotally mounted in the lock housing; a vertically movable member disposed in the trigger bow in front of the trigger and slidably engaged with a part of the housing to be guided thereby; a lever pivotally connected to said member and having one end engageable with the top face of the trigger to provide a pivotal suspension mounting for said member on said trigger face; a depending projection on the lock frame; and a spring bearing against the other end of the lever to normally hold its first-named end in such engagement, said sliding member being normally held in raised position with its upper end engaged with said projection to secure the lock frame in the housing.
14. In an automatic pistol, the combination of a movable barrel; a bolt slidable therein and adapted to recoil when the pistol is fired; a member for coupling the barrel and bolt together; a trigger; a hammer; means for cocking the hammer; a pri-

mary sear for keeping the hammer in its cocked position and adapted to be disengaged from the hammer as long as the trigger is kept pulled; and a secondary sear 5 adapted to hold the hammer in its cocked position during the recoil of the bolt and to be moved out of engagement with the ham-
mer by the coupling member when said bolt returns from the recoil into its front position.

In testimony whereof I affix my signature.

FIDEL FEEDERLE.
